UNITED STATES PATENT OFFICE.

ALEXANDER L. PENO, OF CHICAGO, ILLINOIS.

SHEET-CARRIER FOR PRINTING-PRESSES.

1,031,465.

Specification of Letters Patent.

Patented July 2, 1912.

Application filed January 10, 1912. Serial No. 670,431.

To all whom it may concern:

Be it known that I, ALEXANDER L. PENO, a citizen of the United States, and resident of Chicago, county of Cook, and State of Illinois, have invented certain new and useful Improvements in Sheet-Carriers for Printing-PresSES, of which the following is a specification, and which are illustrated in the accompanying drawings, forming a part thereof.

The invention relates to printing presses and more specifically to the device employed for transferring sheets, commonly known as the fly.

As ordinarily used the fly of a printing press comprises a plurality of strips arranged at intervals along an oscillating bar or shaft to which they are attached at one end only. In the use of this device the sheets are held against the strips by the pressure of the air against the sheet as it is moved. In some instances, as when the sheets are of thin paper, this pressure of the air depresses the sheet between the strips or sticks, thereby interfering with the deposit of the sheets upon a pile while the end portions of the sheets are sometimes deflected completely through the fly and prevent the separation of the sheet therefrom.

The object of the invention is to improve the construction of the fly of a printing press whereby sheets of any character are caused to rest smoothly against the fly during its movement.

The invention contemplates a clip of special construction adapted to be removably applied to the fly sticks of a printing press for bridging the space between the sticks whereby a continuous support is provided for the sheet.

A detail of the invention provides a stop for engaging the edge of the sheet to determine its position upon the fly.

In the accompanying drawings;—Figure 1 is a perspective view illustrating a detail of a printing press and showing the fly equipped with devices constructed in accordance with the invention; Fig. 2 is an inverted plan view of one of the devices provided by the invention; Fig. 3 is a sectional view of the same taken on the line 3—3 of Fig. 1, and Fig. 4 is a plan view showing a sheet metal blank from which the device illustrated in Figs. 2 and 3 may be formed.

A detail of one of the side frame members of a printing press is shown in the drawings

at 10. The fly of the printing press is generally designated by the numeral 11. This fly comprises an oscillatable bar or shaft 12 and a plurality of fly sticks 13 arranged at 60 intervals along the bar 12 and projecting laterally therefrom. The bar 12 is equipped with trunnions, as 14, at its opposite ends. These trunnions are journaled in the side frame members, as 10, of the press. The fly 65 is oscillated by a crank 15 applied to the trunnion 14.

The invention provides a plurality of spring clips, as 16, 17, 31 and 32 adapted to be applied to the fly sticks 13. Each of 70 these clips has laterally projecting arms 18, 19, for bridging the space between the fly sticks and providing a support for the sheets laid upon the fly. The clips, as 16, 17, 31 and 32 are preferably formed by folding a 75 sheet metal blank of the form shown at 20, Fig. 4.

The blank 20 is illustrated as being provided with a plurality of pairs of lateral wings 21, 22 and 23, 24. In the formation 80 of the clips these wings are inwardly folded and the intermediate portion 25 of the blank flexed in the manner illustrated in Fig. 3 of the drawings. The arms 18, 19 of the clip are preferably formed upon the blank 20 85 intermediate the pairs of wings 21, 22 and 23, 24.

As thus constructed the clip may be applied to any one of the strips or sticks 13 of the fly 11 by passing the clip longitudinally over the end of the stick, the wings 21, 22 and 23, 24 serving to embrace and frictionally grip the stick to prevent dislodgment of the clip thereon. When thus applied the wings 18, 19 extend laterally in 95 opposite directions toward the adjacent sticks and provide a support for that part of the sheet which rests between the sticks. In event the space between adjacent sticks 13 of the fly 11 is not available for receiving 100 one of the arms, as the arms 18 of the clips 31 and 32 as by the presence of one of the delivery tapes 26 of the printing press, the arm 18 may be bent downwardly to occupy a position parallel with the wings 21, 23 or 105 24, 25.

Preferably the intermediate portion 25 of the blank 20 is extended at one end beyond the adjacent pair of wings, as 23, 24 to provide a tongue 27. If desired this tongue 110 may be bent upwardly, as illustrated upon the clips 17 and 32 shown in Fig. 1 to pro-

vide a stop for engaging the edge of the sheet. In some instances, it may be desirable to provide the parts of the clip with instanding barbs for enabling it to take a more secure hold upon the stick 13 to which it is applied. As shown, barbs 28, 29 and 30 for this purpose are provided upon the intermediate portion 25 and upon the wings 21, 22, 23 and 24 of the clip by indenting the material of the clip at these places with a punch.

In practice a plurality of clips of the form provided by the invention will be employed upon the fly of a printing press. Usually a small number of devices will be sufficient to insure a support for the sheet such as will prevent it from being depressed between the sticks of the fly. Fig. 1 of the drawings shows four of the devices applied to the fly 11, two upon each of two of the sticks 13. In event the sticks 13 to which the devices are applied are those which engage the sheet adjacent its ends, this number will ordinarily be sufficient to serve the purpose intended. Obviously, the several devices may be located in various positions upon the fly in accordance with the size and character of the printed sheets. The stops 27 provided by turning up the end portions of the clips 17 and 32 are useful when thick sheets, as cardboard, are being printed, for without these stops sheets of this character are frequently displaced upon the fly during its movement.

35 I claim as my invention—

1. A spring clip adapted to be applied to a fly stick of a sheet delivery mechanism and comprising in combination, a pair of oppositely bowed elastic arms for embracing and gripping the fly stick, and a laterally extending sheet supporting arm for bridging the space at one side of the stick, all of said arms being formed from an integral blank of sheet metal.

45 2. A sheet carrier adapted to be applied to a fly stick of a sheet delivery mechanism and comprising in combination, a body, gripping arms for engaging the fly stick, a pair of oppositely directed laterally projecting sheet supporting arms and a longitudinally directed flexible tongue, all of said arms and said tongue being carried by the said body.

3. In combination with a sheet delivery fly, a flexible tongue extending longitudinally with respect to the fly and secured thereto adjacent one of its ends, the said tongue being adapted by reason of its flexibility to be bent into positions in which it

lies flat against the face of the fly and in which it projects upwardly from the said face of the fly to serve as a stop for the edge of a sheet, respectively.

4. A sheet carrier adapted to be applied to a fly stick of a sheet delivery mechanism and comprising, in combination, a longitudinally directed flexible sheet metal tongue adapted by reason of its flexibility to be bent into positions in which it lies flat against the face of the fly and in which it projects upwardly from the said face of the fly to serve as a stop for the edge of a sheet, respectively, and arms for elastically embracing and gripping the fly stick formed integral with the said tongue adjacent one of its ends.

5. A spring clip adapted to be applied to a fly stick of a sheet delivery mechanism and comprising, in combination, a pair of oppositely bowed elastic arms for embracing and gripping the fly stick and a pair of oppositely directed laterally extending sheet supporting arms for bridging the space at the two sides of the fly stick, all of said arms being formed from an integral blank of sheet metal.

6. A spring clip adapted to be applied to a fly stick of a sheet delivery mechanism and comprising, in combination, a pair of oppositely bowed elastic arms for embracing and gripping the fly stick, a pair of oppositely directed laterally extending sheet supporting arms for bridging the space at the two sides of the fly stick, and a longitudinally directed flexible tongue adapted by reason of its flexibility to be bent into positions in which it lies flat against the face of the fly stick and in which it projects upwardly from the said face of the fly stick to serve as a stop for the edge of the sheet respectively, all of said arms and said tongue being formed from an integral blank of sheet metal.

7. A sheet carrier for attachment to a fly stick of a sheet delivery mechanism comprising, in combination, an attaching clip for engaging the fly stick and a flexible arm carried by the clip, said arm being adapted by reason of its flexibility to be bent into positions in which it projects laterally from the clip in the plane of the front face of the fly stick to bridge the space at one side of the fly stick and in which it hugs the side of the stick respectively.
